FIG. 1 shows a perspective view of luggage with its handle in a retracted configuration;

FIG. 2 shows a front view thereof;

FIG. 3 shows a rear view thereof;

FIG. 4 shows a right side view thereof;

FIG. 5 shows a left side view thereof;

FIG. 6 shows a top view thereof;

FIG. 7 shows a bottom view thereof;

FIG. 8 shows a right side view thereof in a partially open configuration and with the handle in a protracted configuration;

FIG. 9 shows a front interior view thereof in an open configuration showing a laundry bag of the design in a deployed configuration; and,

FIG. 10 shows a front interior view thereof in an open configuration showing a compression pad exposed and the laundry bag of the design in a stored configuration.

The broken lines shown in the drawings represent unclaimed portions of the luggage and form no part of the claimed design.

1 Claim, 10 Drawing Sheets
